Inventor:
Jacob Kaufmann,
By Jas. C. Nobeon with
Attorney.

UNITED STATES PATENT OFFICE.

JACOB KAUFMANN, OF PHILADELPHIA, PENNSYLVANIA, ASSIGNOR TO STEEL HEDDLE MANUFACTURING COMPANY, OF PHILADELPHIA, PENNSYLVANIA, A CORPORATION OF PENNSYLVANIA.

HEDDLE.

1,379,824.

Specification of Letters Patent. Patented May 31, 1921.

Application filed March 18, 1921. Serial No. 453,519.

To all whom it may concern:

Be it known that I, JACOB KAUFMANN, a citizen of the United States, residing at Philadelphia, in the county of Philadelphia and State of Pennsylvania, have invented certain new and useful Improvements in Heddles, of which the following is a specification.

My invention relates to heddles for loom harness, and particularly to that type of heddle which is made from a thin, flat strip of metal or wire having a central eye for the control of the warp, and mortises at the ends thereof for mounting the heddles on the supporting bars or rods of the frame.

The object of my present invention is to provide an improved form of heddle of such construction whereby one or more heddles may be mounted in the frame at desired locations, either for the purpose of replacing a broken or damaged heddle, or where it is desired to increase the number of heddles in the frame, and without dismantling the supporting bars or rods from the harness frame.

The nature and characteristic features of my invention will be more readily understood from the following description, taken in connection with the accompanying drawings forming part hereof, in which—

Figure 1 is an edge view of a heddle embodying the main features of my present invention, the same being shown mounted on the supporting bars or rods of the harness frame;

Fig. 2 is a face view of the heddle shown in Fig. 1, the supporting bars being shown in section;

Figs. 3 and 4 are enlarged face views of the upper and lower mortised end portions, respectively, of the heddle of my present invention; and

Figs. 5 and 6 are perspective views of the upper and lower end portions, respectively, of the heddle, the same being shown in the act of being mounted on their respective heddle supporting bars.

Referring to the drawings, in the particular embodiment of my invention therein shown, 7 is the main or body portion of the heddle, which is made from a thin, flat strip of metal or wire, and in which the central warp controlling eye 8 is formed by slitting and expanding the strip in any preferred manner,

Near each end of the heddle, there is provided a mortise 9, which is formed by slotting the same, the slot being of a sufficient width to permit the heddle to freely move on the supporting bar, and of a length to permit a slight up and down movement of the heddle with respect thereto. The mortise 9 is located off-center with respect to the side edges of the flat strip from which the heddle is formed, whereby there will be provided, on one side of the mortise 9, a strip 10 of a width appreciably greater than that of the strip 11 left on the other side of the mortise. The narrower strip 11 on one side of the mortise is transversely cut or slit as at 12, which slits are preferably located near the lower ends of the mortises at the top and bottom respectively, to thereby provide, at each mortise, a short length 13 of the metal extending upwardly above the lower end of each mortise.

The strips 10 and 11 forming the shanks on each side of the mortise 9 are preferably also provided with offset portions 14, formed by bending the metal in any preferred shape out of the main plane of the strip of which the heddle is formed, the purpose of the offset portions 14 being to prevent rotative movement of the heddle proper with respect to the supporting bars 15.

By the arrangement above described, there will be provided an improved type of heddle which may be conveniently and expeditiously mounted on the heddle supporting bars at desired locations, without necessitating the removal of the supporting bars from the harness frame. When it is desired to mount one of said heddles on the supporting bars, the heddle is brought with the upper mortise adjacent the upper supporting bar 15, and with the slit 12 of the shank 11 near the upper edge of said supporting bar, whereupon the relatively narrow strip or shank 11 may be slightly sprung out of its normal position to straddle the supporting bar 15 (see Fig. 5), and the heddle is then pulled downward until the slit 12 passes the lower edge of the supporting bar 15, whereupon the shank 11 may be permitted to resume its normal position, and the upper end of the heddle will be then properly mounted on its supporting bar 15. Similar procedure may now be followed at the lower end of the heddle, namely, the slit 12 is

brought adjacent the upper edge of the lower supporting bar 15, whereupon the relatively narrow shank 11 of the mortise at the lower end of the heddle may be sprung out of its 5 normal position, to straddle the lower supporting bar 15, and the lower end of the heddle may then be pushed downward until the slit 12 thereof passes the lower edge of the lower supporting bar 15, whereupon 10 the narrow strip 11 may then be permitted to resume its normal position and the lower end of the heddle will then also be properly mounted on its supporting bar 15.

It will be noted that by this arrangement 15 the heddle may be readily mounted in the frame at any desired location without unduly straining the heddle or the supporting bars, and when so mounted, the location of the slits 12 is such that there is no possibility 20 of fouling the warp ends which pass adjacent a heddle of this construction, because, when the frame is in the uppermost position in the loom, the slit 12 at the lower end of the heddle will be located below the upper 25 edge of the lower supporting bar. Furthermore, the portions 13 at the lower end of each of the mortises will serve to support the heddle with respect to the supporting bars when the strain is reversed, that is, 30 when the frame is at its lowermost position in the loom, in this manner preventing accidental disengagement of the heddle therefrom. Furthermore, by locating the mortise 35 9 at each end of the heddle off-center with respect to the side edges of the strip, the relatively wider shank 10 forming the solid side of the mortise will afford the requisite degree of stiffness and thereby maintain the mortised ends of the heddle against bending 40 and deformation.

Having thus described the nature and characteristic features of my invention, what I claim as new and desire to secure by Letters Patent, is:

45 1. A heddle made from a thin, flat strip of metal having mortises near the ends thereof for mounting the same on the heddle supporting bars, said mortises being formed by slotting the strip from which the heddle 50 is formed, leaving strips on each side of each mortise, and one of the strips of each mortise being transversely slotted to permit the heddle being mounted on the supporting bars without removing said bars from the frame.

55 2. A heddle made from a thin, flat strip of metal having mortises near the ends thereof for mounting the same on the heddle supporting bars, said mortises being formed

by slotting the strip from which the heddle 60 is formed, leaving strips on each side of each mortise, and one of the strips of each mortise being transversely slotted near one end thereof to permit the heddle being mounted on the supporting bars without 65 removing said bars from the frame.

3. A heddle made from a thin, flat strip of metal having mortises near the ends thereof for mounting the same on the heddle supporting bars, said mortises being formed 70 by slotting the strip from which the heddle is formed, leaving strips on each side of each mortise, and one of said strips of each mortise being transversely slotted near the lower end thereof to permit the heddle being 75 mounted on the supporting bars without removing said bars from the frame.

4. A heddle made from a thin, flat strip of metal having mortises near the ends thereof for mounting the same on the heddle 80 supporting bars, said mortises being located off-center with respect to the side edges of the heddle, to thereby provide strips on each side of each mortise one of which is of an appreciably greater width than the other, 85 and the strip of narrower width being transversely slotted to permit the heddle being mounted on the supporting bars without removing said bars from the frame.

5. A heddle made from a thin, flat strip 90 of metal having mortises near the ends thereof for mounting the same on the heddle supporting bars, said mortises being located off-center with respect to the side edges of the heddle, to thereby provide strips on each side of each mortise one of which is of an appreciably greater width than the other, 95 and the strip of narrower width being transversely slotted near one end thereof to permit the heddle being mounted on the supporting bars without 100 removing said bars from the frame.

6. A heddle made from a thin, flat strip of metal having mortises near the ends thereof for mounting the same on the heddle 105 supporting bars, said mortises being located off-center with respect to the side edges of the heddle, to thereby provide strips on each side of each mortise one of which is of an appreciably greater width than the other, 110 and the strip of narrower width being transversely slotted near the lower end thereof to permit the heddle being mounted on the supporting bars without removing 115 said bars from the frame.

In testimony whereof, I have hereunto signed my name.

JACOB KAUFMANN.
